UNITED STATES PATENT OFFICE

142,776

DESIGN FOR A COMBINED PIPE RACK AND MATCH HOLDER

William H. J. Downey, Wilmington, Del.

Application July 7, 1945, Serial No. 120,554

Term of patent 7 years

(Cl. D85—2)

To all whom it may concern:

Be it known that I, William H. J. Downey, a citizen of the United States, residing at Wilmington, in the county of New Castle and State of Delaware, have invented a new, original, and ornamental Design for a Combined Pipe Rack and Match Holder, of which the following is a specification, reference being had to the accompanying drawing, forming part thereof.

Figure 1 is a view in top plan of a combined pipe rack and match holder embodying the new design;

Figure 2 is a view in front elevation; and
Figure 3 is a view in end elevation.

I claim:

The ornamental design for a combined pipe rack and match holder substantially as shown.

WILLIAM H. J. DOWNEY.
